Charles E. Dey
INVENTOR

UNITED STATES PATENT OFFICE.

CHARLES E. DEY, OF DENVER, COLORADO.

ANNUNCIATOR.

SPECIFICATION forming part of Letters Patent No. 323,921, dated August 11, 1885.

Application filed September 1, 1884. (No model.)

To all whom it may concern:

Be it known that I, CHARLES E. DEY, of the city of Denver, in the county of Arapahoe and State of Colorado, and a citizen of the United States, have invented a new and useful Improvement in Electro-Magnetic Annunciators.

The object of my invention is to provide an annunciator for the use of hotels and other buildings by which the number of the room or rooms from which the call is made may be indicated upon the dial; and I hereby declare the following to be a true description thereof, which will enable others skilled in the art to 10 which my invention appertains to make the same, reference being had to the accompanying drawings, forming part of this specification, in which—

Figure 1 is a front view of my annunciator. 20 D represents the dial-plate; X, the annunciator-case. A, B, and C represent three (3) metal indicators on the dial-plate. Indicator A has the movable cover E to one side, leaving the stationary metal pointer H, which is 25 attached to the dial-plate D, pointing to the figure 1, representing a room. The figure 1 is painted on the dial-plate.

Figs. 2 and 3 are the front and side views, respectively, of the electro-magnetic arrangement I use in operating my movable cover E. 30 b in both Figs. 2 and 3 represent the metal back. s and s are screws holding the back to the dial-plate. M and M' are two (2) electro-magnets. They are screwed to two (2) 35 upright ends cast solid with the back. U is an iron plate with holes for the screws to go through, which screws hold the magnets to the upright ends of the metal back. U serves as a keeper. A represents an armature made 40 of Norway iron, which is held to the back b by the screw l', which goes through a hole in the armature and screws in the back b, leaving the armature free to move up and down against the ends of the cores of the magnets M and M'.

45 O is an upright piece cast solid with the back. Through O a screw, l, goes for raising and lowering the armature a. W is a metal piece held

by the armature a, as shown in Fig. 2, which is screwed on an end of pin P. (Shown in Fig. 3.) The pin P goes through a hole in the 50 metal back b, on through a hole in the dial-plate D, then through a hole in the pointer H, and has screwed on the other end the cover E, with the nut N screwed on the top of the cover E. The metal back b is screwed close to the 55 dial-plate D, and is placed apart from the dial-plate in Fig. 3, in order to show the two parts as being different. The pointer H is a metal piece soldered to a nut and then screwed to the dial-plate. Both nut and pointer have a 60 hole in the center for the pin P to turn in.

Supposing the annunciator-magnets to be connected with batteries and pushes in rooms, the operation is as follows: When the electric circuit is closed by a push from a room, the 65 electro-magnets M and M' draw the armature a up to the ends of the cores of the magnets. The metal piece W, which is held by the armature a, then drops, causing the cover E to move to one side, as shown in Fig. 1. The cover E and piece W, being screwed on the two ends of the same pin P, the cover E moves on the dial-plate the same distance as the piece W falls. The distance W falls is regulated by an arrangement I use for throwing the piece W 70 back again. This arrangement it is not necessary to describe in order to get an understanding of my invention.

Now, having thus described my invention, what I claim as new, and desire to secure by 80 Letters Patent, is—

The combination of a stationary metal pointer attached to the dial-plate with numbers painted on the dial-plate just below the end of the pointer, and a movable metal cover covering the pointer and number, which can be turned to one side and operated by an electro-magnetic arrangement behind the dial-plate, making an indicator, as shown, for the purpose set forth.

CHARLES E. DEY.
